UNITED STATES PATENT OFFICE.

WILLIAM PHILLIPS, OF AUBURN, ILLINOIS.

NEEDLE.

1,390,924.

Specification of Letters Patent. Patented Sept. 13, 1921.

Application filed March 24, 1920. Serial No. 368,356.

To all whom it may concern:

Be it known that I, WILLIAM PHILLIPS, a citizen of Russia, residing at Auburn, in the county of Sangamon and State of Illinois, have invented certain new and useful improvements in Needles; and I do hereby declare the following to be a full, clear, and exact description of the invention, such as will enable others skilled in the art to which it appertains to make and use the same.

This invention relates to new and useful improvements in needles used by shoemakers and of the character having a hook which may be closed by a slide, and has for one of its objects the provision of means for securing the slide to the needle which permits of free movement of said slide without the liability of the same becoming detached from the needle and also whereby the slide can be removed or replaced in the needle when desired.

Another object of this invention is the provision of a needle of the above stated character, which shall be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawings, in which—

Figure 1 is a side elevation of a needle constructed in accordance with my invention,

Fig. 2 is a transverse sectional view taken through the needle illustrating the closing slide,

Fig. 3 is a plan view partly in section of the needle, illustrating the means of securing the shank to the handle,

Fig. 4 is a fragmentary sectional view of the needle and handle.

Fig. 5 is a transverse sectional view taken through the needle holding clamp.

Referring in detail to the drawings, the numeral 1 indicates the body of a needle having a pointed end 2 provided with a hook 3. The other end of the body 1 is enlarged to form a shank 4 which has its outer face beveled or inclined as illustrated

at 5. The body 1 has formed therein a groove 6 which extends from a point adjacent the hook 3 and also extends through the shank 4 opening outwardly of the shank 60 so as to slidably receive a slide 7. The walls of the slot 6 are inclined as clearly illustrated in Fig. 2, while the walls of the slide are inclined oppositely to lock the slide against removal from the slot but which 65 will permit free movement of the slide within the slot. The slide has its outer face serrated as illustrated at 9 and these serrations project beyond the body so that a person's finger can readily engage the same for 70 the purpose of shoving the slide in the direction of the hook 3 so as to close the same. In order to remove the slide from the groove 6 it is necessary that the same be pulled outwardly through the end of the shank 4 75 and reinstated within the slide in the same manner.

A handle 10 has secured to one end in any well known manner a set of spaced arcuate gripping jaws 11 preferably two in number 80 and which have their outer faces screw threaded as illustrated at 12 and are constructed of resilient material. A locking collar 13 is provided with internal screw threads and is adapted to be threaded on 85 to the jaws for compressing the jaws against the inclined faces 5 of the shank 4, so as to positively lock the body 1 to the handle and providing a construction wherein the needle or body 1 can be readily detached from the 90 handle when desiring to remove the slide. It is to be noted that the slide is limited in its rearward movement by the front wall or terminal 14 of the jaws 11.

In operation the needle with the slide 95 moves rearwardly and passes through the leather of a shoe when repairing the shoe or making the same, and the thread then may be caught by the hook and the hook closes by moving the slide in engagement 100 with the same, permitting the thread to be drawn through the leather without danger of becoming detached from the hook.

From the foregoing, it will be seen that this simple and inexpensive form of needle 105 is provided which may be readily employed by shoemakers and the like and operated by one hand, thereby leaving the other hand free to hold the work. It will further be seen that the clamping jaws 11 may be 110 readily adjusted upon and tightened on the shank or body 4 of the needle and any of

the parts may be readily replaced at small cost, if required. It will further be noted that the longitudinal side edge of the eye closing member which is fitted for longitudinal sliding movement upon the shank of the tool for effecting the opening and closing of the eye of the needle, projects from the surface of the shank sufficiently to insure the contact thereof with the wall of the puncture in the leather or other material penetrated by the end or eye pointed extremity of the needle, so that in inserting the tool into the puncture of the leather the frictional contact of said slide with the wall of the opening serves to move the slide backward to open the eye of the needle whereas after the thread has been engaged with the eye, the first effect of the backward movement of the needle in withdrawing it from the puncture is to slide the closing member in the opposite direction to close the eye and effectually retain the slide in an eye closing position while the needle is being withdrawn. Thus in the operation of the tool constructed as described the opening of the eye is effected by the insertion of the needle into the puncture of the material and the closing of the eye is effected by the withdrawing of the tool, and the certainty of this operation is insured by roughening or serrating the projecting surface or edge of the slide as hereinabove described and as clearly indicated in the drawings. An independent or manual operation of the eye closing slide, either to effect the closing or opening movement thereof, is rendered unnecessary by providing the eye closing member with a projecting frictional surface disposed longitudinally of the shank and

extending to a point near the eye of the needle, so that even though the needle is introduced only a short distance into the puncture of the leather or other material, or is extended only a sufficient distance to disclose the eye for the reception of the thread, it is sufficient to cause the retraction of the slide and hence the opening of the eye.

While I have shown and described the preferred embodiment of my invention, it will be understood that minor changes in construction, combination and arrangement of parts may be made without departing from the spirit or scope of the invention as claimed.

Having thus described my invention, what I claim is:—

A device of the class described including a handle, a needle having a penetrating end member, means to detachably secure the needle to the handle, said needle having a slot extending inwardly from the inner end, an eye closing member slidable in the slot and removable therefrom at the inner end of the needle, said eye-closing member being held against displacement in one direction by engagement with the said end member, said means crossing the slot, and said eye-closing member being engageable with said means to prevent accidental displacement from the slot at the inner end of the needle.

In testimony whereof I affix my signature in presence of two witnesses.

WILLIAM PHILLIPS.
